UNITED STATES PATENT OFFICE

164,121

LOUD-SPEAKER HOUSING

Duncan N. MacDonald, Evanston, Ill., assignor to
Automatic Electric Laboratories, Inc., Chicago,
Ill., a corporation of Delaware

Application April 5, 1950, Serial No. 8,985

Term of patent 14 years

(Cl. D26—14)

To all whom it may concern:

Be it known that I, Duncan N. MacDonald, a citizen of the United States, residing at Evanston, State of Illinois, have invented a new, original, and ornamental Design for a Loud-Speaker Housing, of which the following is a specification, reference being had to the accompanying drawing, forming a part hereof.

Fig. 1 is a perspective view of the loud-speaker housing illustrating the new design comprising the present invention.

Fig. 2 is a perspective view of the same loud-speaker housing showing the side and rear which is hidden from view in Fig 1.

I claim:

The ornamental design for a loud-speaker housing, as shown.

DUNCAN N. MACDONALD.
